UNITED STATES PATENT OFFICE.

JOHN R. HAMILTON, OF YONKERS, NEW YORK, ASSIGNOR TO AUTOMATIC SPRINKLER COMPANY OF AMERICA, OF NEW YORK, N. Y., A CORPORATION OF NEW YORK.

DESIGN FOR A FRAME FOR A SPRINKLER-HEAD OR SIMILAR ARTICLE.

55,170.

Specification for Design.

Patented May 18, 1920.

Application filed July 22, 1919. Serial No. 312,580. Term of patent 14 years.

To all whom it may concern:

Be it known that I, JOHN R. HAMILTON, a citizen of the United States, residing in Yonkers, county of Westchester, State of New York, have invented a new, original, and ornamental Design for a Frame for a Sprinkler-Head or Similar Article, of which the following is a specification, reference being had to the accompanying drawing, which forms part of the same, and in which—

Figure 1 is an elevation of a frame for a sprinkler head or similar article of manufacture embodying my new design; and

Fig. 2 is a perspective view thereof taken at a somewhat different angle.

What I claim is:

The ornamental design for a frame for a sprinkler head or similar article, substantially as shown.

JOHN R. HAMILTON.
